Term of patent 14 years

(Cl. D33—7)

FIGURE 1 is a front perspective view of an L-shaped desk unit or similar article, showing our new design.

FIGURE 2 is a rear perspective view thereof; and

FIGURE 3 is a fragmentary perspective view of the leg structure.

The dominant features of the design reside in the portions shown in full lines in the drawing and are characterized by legs of angular cross section which are recessed into the side panels and spaced from the adjacent edges of the panel, in combination with the framed panels on the front and rear faces, of the pedestals, substantially as shown.

The end of the desk unit not completely shown is the same in appearance as the end shown while the inner faces of the drawer pedestals are substantially plain.

We claim:

The ornamental design for an L-shaped desk unit or similar article, substantially as shown and described.
